UNITED STATES PATENT OFFICE.

CHARLES SETZEFANT, OF MODESTO, CALIFORNIA.

ELECTRIC HEATING SYSTEM FOR OIL PIPE LINES.

Application filed August 10, 1927. Serial No. 211,928.

My invention is an electric heating system for oil pipe lines.

It is necessary for many localities where oil is transported in pipe lines to heat the oil in order to cause it to flow more readily. My invention comprises an electric heating system by which the heat is derived from an electric current and heats the oil when passing through the system.

10 A further object of my invention is to heat the oil while passing through a series of small pipes by the flow of air around the pipes, such air having been previously heated by electric heating units which may be 15 of any suitable character.

Another object of my invention is utilizing a structure with my heating appliance therein, constructed somewhat after the manner of a boiler or furnace, so that boiler 20 or furnace structures may be remodeled using my electric heating system.

Another object of my invention is ascertaining the temperature of the oil by means of a pyrometer and regulating the electric 25 current in the electric heating units to maintain the oil at the desired temperature.

My electric heating system comprises preferably a brick structure having front, rear and side walls and a roof. The floor 30 has a low section in front and a raised section at the rear. In the low section there are a series of heating coils operated electrically, the air coming in around and below these coils. The transmission pipe line enters the back and the front of the furnace 35 where it is connected to cone-shaped enlargements which have header plates at the large end. Between these plates there are a considerable number of small pipes sufficient to carry the flow of oil without unduly retarding its flow. The pipes pass through intermediate disks which are supported on brackets from the raised part of the floor. The air entering the front and lower part 40 of the furnace is heated by the electric heating units, circulates and passes around the separate small pipes and is discharged through a stack.

My invention is illustrated in the accompanying drawings, in which:

Figure 1 is a longitudinal section through my heating appliance.

Figure 2 is a vertical transverse section on the line 2-2 of Fig. 1 in the direction of the arrows.

The furnace structure comprises a front

wall 11, a rear wall 12, side walls 13, a top 14 and a floor 15. This floor has a low section 16 in the front and a high section 17 towards the rear of the furnace. The front 60 of the furnace is provided with an opening 18 to which is secured a door 20 allowing access into the furnace structure, and also has an open portion 21. A stack 22 extends upwardly from the rear end of the furnace 65 and has a damper 23 therein.

The transmission pipes 24 and 25 pass through wall sections 26 built into the front and rear walls 11 and 12 of the furnace, these preferably having connecting flanges 70 27. Inside of these sections there are coned sections of pipe 28 which have header plates 29. These header plates support a series of small pipes 30, the header plates having openings in which the ends of such pipes fit. 75 Spaced longitudinally of the pipes 30 there are one or more disks 31 formed preferably of metal plate with perforations therethrough to accommodate the pipes. These disks are supported on bridges 32 which rest 80 on the high section 17 of the rear part of the furnace; thus giving ample support to the pipes in the center part of the furnace.

The electric heating system comprises a series of heating units 33 which are mounted on a grate like structure 34 mounted above the low part of the floor 16. These heating units are connected by suitable conducting cables 35 to an electric controller 36 which may be manually operated or automatically controlled if desired. In order to register the temperature of the oil a pyrometer 37 is fitted in one of the coned sections of the oil pipe, preferably at the discharge end, and is connected by electric cables 38 95 with a register 39.

The manner of operation and functioning of my electric pipe line is substantially as follows:

It will be understood that the oil is 100 pumped or otherwise forced through the system and the electric current passing through the heating units heats these to the temperature for which they are designed or which is desired. Air enters through the 105 openings 21 in the front of the furnace and passing around the heating units becomes heated to a very high degree. This air then travels through the furnace space, some of it encircling the coned ends 23, but the major 110 portion passing around the series of pipes which connect the header plates. As these

pipes contain oil in the relatively small cross-section, the heat is readily interchanged between the air and the pipes, thence to the oil in the pipes.

- 5 The hot air is baffled to a certain extent by the supporting disks 31 and may be caused to have an irregular path up and down and longitudinally of the pipes. The air discharges through the stack 22 which 10 is controlled by the damper 23. The position of this damper regulates the outflow of air so it is not necessary to regulate the inflow through the openings 21.

The pyrometer 37 adjacent the discharge end of the system gives a reading of the register 39 of the temperature of the oil, hence the operator may regulate the controller 36 which governs the amount of electric current passing to the headers; thereby the oil 20 may be kept at the desired constant temperature or the temperature may be either increased or decreased in accordance with a predetermined plan.

It will thus be seen that I have developed 25 a simple type of apparatus for heating oil, and that the heating units may be readily installed and got at for repairs. The air may be readily regulated and the use of heating units for heating the air and the 30 air transferring heat to the oil allows my equipment to be used in old styles of furnaces, by remodeling these to install the electric heating units and a series of small pipes connected to the pipe lines.

35 Various changes may be made in the principles of my invention without departing from the spirit thereof, as set forth in the description, drawings and claims.

I claim:

40 1. In the art described, the combination of a furnace structure having an oil pipe line connected through the ends of the furnace, a series of smaller pipes connecting the pipe lines in the furnace, electric heating units in the furnace, a stack, and means to control the flow of air through the furnace over the heating units and around said smaller pipes.

45 2. In the art described, the combination of a furnace having front and back walls, a pipe line entering the furnace through said walls, a cone-shaped unit connected to each of the pipes, a series of smaller pipes connected to the coned structures, a stack connected to the roof of the furnace, a plurality of electric heating units in the base of the furnace, and a passage for air entering underneath said heating units, the air passing upwardly around said units, around said 55 pipes and out the stack.

60 3. In the art described, the combination of a furnace having front and back walls, a pair of oil pipe lines entering through said walls, each having a coned pipe section connected thereto with a header plate forming

the base of each coned section, a plurality of smaller pipes connecting said header plates, an inlet for air near the base of the furnace at one end, a stack connected to the roof of the furnace at the other end, a series 70 of electric heating units above the air inlet, the air passing around the heating units, heating the small pipes and leaving through the stack.

4. In the art described, as claimed in 75 claim 3, an electric thermostat in one of the coned pipe sections, a register connected to said thermostat, and a controller for the electric heating units.

5. In the art described, as claimed in 80 claim 3, a plurality of disks through which the said smaller pipes pass, and bridges connected to the floor of the furnace and supporting said disks.

6. In the art described, the combination of 85 a furnace having front and back walls, a floor having a lower section towards the front and a higher section towards the rear, a stack extending through the roof and air inlet through the lower part of the front, a 90 pair of oil pipes in the front and back walls, coned pipe sections connected thereto at the front and back of the furnace, each having a header plate on its base, a plurality of smaller pipes connecting the header plates, 95 electric heating units in the front of the furnace adjacent the lower part of the floor, the air passing upwardly through said heating units and circulating around the smaller pipes and passing out of the stack. 100

7. In the art described, the combination of a furnace having front and back walls, a floor having a low front section and a raised rear section, there being an air opening in the front wall near the floor, a stack forming 105 an outlet through the roof, a pair of oil pipes entering through the front and back walls and having coned pipe sections connected thereto, each having a header plate forming the base, a series of smaller pipes 110 connecting said header plates, a plurality of disks on said smaller pipes through which said pipes pass, a bridge for each disk connected to the upper section of the floor, a plurality of electric heating units positioned 115 above the front lower floor section, the air passing upwardly through said heating units, circulating around the smaller pipes and having an outlet through the stack. 120

8. In the art described, as claimed in claim 7, an electric thermostat mounted in one of the coned pipe sections, an indicator mounted on the roof and connected to said thermostat, a controller mounted on the roof and having an electric connection to the electric 125 heating units.

In testimony whereof I have signed my name to this specification.

CHAS. SETZEFANT.
